DES. 2225

Leonidas Macneir, of Philadelphia, Penna
assigns to

Isaac Townsend, of the same place
Letters Patent No. 2225-Dated Decr 5. 1865
Design for a Match Safe

The schedule referred to in these Letters Patent and making part of the same.

To all whom it may concern:

Be it known that Leonidas Macneir, of the City of Philadelphia, in the State of Pennsylvania, have invented or produced a new and original design for a Match Safe, of which the following is a full, clear and exact description, reference being had to the accompanying drawing, making a part of this specification.

The nature of my design consists in the combined arrangement of a miniature group representing two coal scuttles and the front fender of a grate or fireplace, resting on a shelf attached to a fire board.

In the drawing A.A. are the coal scuttles; B the front fender; C, the fire board; and D, the shelf.

The scuttles A.A. are designed for holding within them the matches, the space behind the fender B, for receiving the charred splints or stems of the matches which have been used, and the shelf D, for supporting the vessels in fixed contact with the fire board C, as represented in the drawing.

Having thus fully described my invention or production.

I claim, as a new and original Design for a Match Safe, the group consisting of the two scuttles A, B, fender, B, fire board C and shelf D, arranged and combined together as set forth and described.

Witnesses:

Benj. Johnson
